UNITED STATES PATENT OFFICE.

EDWARD J. CONKLIN, OF BRIDGEPORT, CONNECTICUT.

KNIFE-BLADE-SQUARING MACHINE.

Application filed January 19, 1923. Serial No. 613,598.

To all whom it may concern:

Be it known that EDWARD J. CONKLIN, a citizen of the United States, and resident of Bridgeport, in the county of Fairfield and State of Connecticut, has invented certain new and useful Improvements in Knife-Blade-Squaring Machines, of which the following is a specification.

This invention relates to new and useful improvements in knife-blade squaring machines, and particularly to a machine for squaring, by grinding, the tangs of pocket knife blades.

It is the purpose of the invention to improve upon machines of this class by designing a machine whereby knife-blade tangs may be squared very much more rapidly than can be done now on other machines for this purpose, and especially to provide a machine wherein the several operations may be performed with one setting of the blade on the machine. It is also an object to provide a machine whereby accuracy and uniformity of operations and production will be assured, and further to so design the machine, that the grinding wheels may be quickly adjusted to perform the required operations upon knife blades having different forms of tangs, and to provide means for feeding the blade to be ground, with relation to the grinding wheels so that the life of the wheels is prolonged, and accuracy in grinding assured.

The invention further comprises a machine which includes three grinding wheels so positioned and spaced with relation to each other, that a movable knife-blade supporting table may be quickly moved from one wheel to the other, to perform the separate operations by a continuous movement of the table and blade, thereby avoiding return and other false movements, and to insure a saving of time in the performance of the work. In this connection I have also included an adjustable setting device whereby the different operations required for grinding the tangs on different styles and sizes of blades may be readily provided. The machine is further constructed so that any one or two of the grinding wheels may be used without the second or third as might be desired in the manufacture of blades where one or two edges only of the tang are required to be ground.

With these and other objects in view the

invention resides and consists in the construction and novel combination and arrangement of parts hereinafter more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification, and upon which,

Fig. 1 shows a front elevation of my improved knife-blade squaring machine;

Fig. 2 is a detail sectional plan view taken on line 2—2 of Fig. 1 showing the pivotal yoke for supporting the movable work table;

Fig. 3 shows a plan view of the machine as seen in Fig. 1;

Fig. 4 is a detail plan of bed of machine, broken away, showing opening therein for movable pedestal carrying work table;

Fig. 5 is a sectional elevation taken on line 5—5 of Fig. 3, illustrating the movable pedestal and its work table, in an operative position;

Fig. 6 is an end elevation, as seen from the right of Fig. 3; and

Figs. 7, 8 and 9 show enlarged diagrammatical views illustrating the manner of grinding the several edges of a knife tang.

In designing the machine shown in the accompanying drawings I have provided separate motors for driving the three separate grinding wheels, though it will be obvious, of course, that these wheels may be belt-driven, and connected to be operated in any well-known or preferred manner, and whereby different speeds and independent control of the wheels may be obtained.

Referring in detail to the characters of reference marked upon the drawing, 10 represents the bed of the machine which is designed to be formed of a single casting, and is supported upon four legs 11 of sufficient height to position the bed and working portions of the machine at a suitable height for the attending operator, when seated on a stool adjacent thereto. The bed is pro-

vided with an angular opening 12 in its front edge, intermediate of the two front legs, to accommodate a movable pedestal for work table 13 upon which the knife blades 5 are carried as will be later again referred to.

14, 15 and 16 represent grinding wheels, which are mounted upon spindles of 10 separate motors designated as 17, 18 and 19. These wheels are substantially alike in construction, each having a bevel edge against which the several edges of the knife tangs are positioned for grinding. Two 15 of the wheels, 14 and 16, are positioned parallel, and are suitably spaced with 20 relation to each other so that the remaining grinding wheel 15 will be slightly to the rear of the first mentioned grinding wheels 14 and 16. The rear grinding wheel is 25 arranged at a right angle to the position of the other two wheels, and is so positioned that its edge will be intermediate of the other two wheels, thus making it possible to first feed the blade A against the wheel 14 for the first operation b, see Figs. 1 and 7, then by a continuous movement, feed it to the second wheel 15 for the second operation c, see Fig. 8, and finally to draw it over the edge of the third wheel 16 for the 30 finishing operation d, see Fig. 9.

The motor frames are respectively secured upon bases 17^a, 18^a, and 19^a that in turn are adjustably supported on the bed 10. Each of these base members is adapted to 35 be adjusted to and from the movable table supporting pedestal. The two wheels 14 and 16 are also adapted to be adjusted forward and backward and at right angles to the aforementioned adjustment, as will be 40 explained.

By this means it will be obvious that each 45 of the wheels may be adjusted edgewise to properly position its cutting edge, and that the wheels 14 and 16 only require to be adjusted backward and forward to assume any required position with relation to each other. Two of these base members 17^a and 19^a are substantially alike in construction, see Figs. 1 and 6, and include ways 21 in 50 their underside to accommodate corresponding ways 22 in slides 23. These slides 23 are provided with longitudinal ways 24 arranged at a right angle to the ways 22 before mentioned, that fit and ride upon ways 25 on the bed. These two base members 17^a and 19^a are provided with depending lugs 26 that are engaged by adjusting screws 27, made to turn in the slides 23, so as to move the base and motor to and fro 55 in a way to adjust the motor and its grinding wheel sidewise. The slides 23 of the base members 17^a and 19^a and also the slide 23 of the base member 18^a, each include a depending lug 29 that is engaged by an 60 adjusting screw 30 mounted in the bed in 65

a manner to provide a backward and forward adjustment to the slide motors and their grinding wheel.

The work carrying table 13 before mentioned, upon which the knife blade A is 70 positioned for its grinding operations, see Fig. 3, is provided with a small upwardly projecting pin 31 to enter the hole a in the tang B of the blade, for the purpose of 75 positioning and holding it while being operated upon. An adjustable guide 32 is secured to the top of the table against which the back edge of the blade is positioned and held by the operator during the grinding operations. Thus it will be seen that the 80 operator positions the blade by registering the hole of the tang on the pin and the back edge of the blade against the guide.

This table is mounted to have a universal movement, that is a movement which 85 enables it to be moved backward and forward and sidewise. This permits the three edges b, c and d of the tang of a knife blade, when mounted upon the table, to be successively fed to the respective grinding 90 wheels, guided by the edges of the opening 12 in the bed of the machine.

This table is carried upon the upper end of an arm 33 of a pedestal 34 carried by a cradle 35 which is mounted in a U-shaped 95 hanger 36 secured to the underside of the bed and directly beneath the opening 12 in the bed. The lower end portion of the cradle member 35 is provided with aligned sockets 28 and 37 that are engaged by the 100 pointed ends of pivotal screws 38 mounted in a yoke 39. The side portions of the yoke are also provided with sockets 40 engaged by aligned pivotal screws 41 seated in the 105 opposite side portions of the before mentioned yoke 39. On the upper end of this cradle 35 is provided a roll 42 which in practice engages the guide plates 43, 44 and 45 secured to the top of the bed of the machine, adjacent to the inner edges of the 110 before mentioned opening 12 formed in the bed. These guide plates serve to limit and 115 guide the movement of the table with reference to the cutting edges of the wheels, as the table is moved by the operator within the opening 12 formed in the bed. The guiding edge of the plate 44 is cut away slightly as at 46 to permit the roll 42 and 120 table to move forward slightly, as is necessary to feed the back d of the tang, in close to the edge of the wheel 16 to slightly undercut the shoulder e, as shown in Fig. 9, in its finishing operation, preparatory to being withdrawn. A cord or chain 20 is used to 125 retain the table and pedestal within limits and prevent it from falling away from the machine. One end of the cord is secured to the bed of the machine and the other end to the cradle as shown in Fig. 5.

The cradle member 35 is provided with 130

oppositely disposed flanges 47—47 which serve as stops against which portions of the pedestal are adjusted and operated as will later be explained. This vertically disposed 5 cradle member 35 includes a channel 48 in which is positioned the pivotally mounted pedestal 34, the two ends of the pedestal being provided with sockets 49 to receive the pointed ends of pivotal screws 50, the 10 lower one of said screws being positioned in the before mentioned yoke 39 and the upper one being positioned in the upper end of the pedestal 34 central of the before mentioned roll 42. The arm 33 which is 15 formed integral with pedestal 34 extends forward and upward from the pedestal and is provided in its upper end with a socket to receive a shank 52 of the table, said shank being adjustably secured therein by 20 means of a set screw 53 (Fig. 5). It will thus be seen that the cradle is supported in the hanger, so that it may be movable backward and forward and sidewise, and that the table carried thereby is provided with 25 all the required movements for the grinding of the blade when carried thereon. I have also provided adjustable means for setting the position of the pedestal and table with 30 relation to the cradle member 35, which means comprises two arms 54 upon opposite sides of the pedestal and provided with screws 55 in each, which screws abut against the flanges 47 before mentioned so that the same may be made rigid with relation 35 thereto, and also provide for a slight independent movement according to the positioning of the screws for the purpose of affording a slight rocker movement to the 40 table, if desired.

45 56 represents an operating handle which is pivotedly mounted at 57 to the upper end portion of the arm 33. This operating handle is thus adapted to move the pedestal and table horizontally, and being pivoted 50 to permit its free outer end to be raised. A link 58 connects the intermediate portion of this arm with a bracket 59 that is also pivotably connected as at 60 to a hub formed on the arm 33. Said 55 bracket further includes depending arms 61 which normally rest against the face of the flanges 47 before mentioned. The purpose of this interlocking connection is to 65 normally support the pedestal 34, its arm 33, and the operating handle 56 in a fixed position with relation to the member 35 to permit definite and uniform manipulations of the table, and to allow slight independent rocker movement of the pedestal 34 70 in cradle 35 should occasion require.

I have mounted a dust shield 62 on the bed 10 beneath the grinding wheels, to cover the roll 42 when in a forward and engaged position. Other shields may obviously be 75 employed to cover the grinding wheels if

desired; as is customary in grinding machines of this class.

Having thus described my invention, what I claim and desire to secure by Letters Patent is:

1. A machine for squaring the tangs of knife blades, comprising a series of grinding wheels, the operating faces of two of which are arranged in opposite relation to each other, a movable knife blade supporting table adapted to be moved as against the operative face of one of the wheels, and then in an opposite direction against the operative face of the other of said wheels to grind the opposite edges of the tang of 75 a blade with one setting of the blade upon the table, and to be moved angularly to said movement between the wheels to grind a portion of the tang against the side of one of said wheels.

2. A machine for squaring the tangs of knife blades, comprising a series of grinding wheels, the cutting faces of two of which are arranged opposite to each other, and the cutting face of the third of which is positioned at substantially a right angle to the first mentioned faces, means for independently adjusting the position of the wheels with relation to each other, a knife blade supporting table adapted to be moved 90 to and from each of the said wheels for separate independent operations upon the tang, and to be moved angularly to said movement between the wheels to grind a portion 95 of the tang against the side of one of said wheels.

3. In a machine for grinding the tangs of knife blades, comprising a series of grinding wheels, the operative faces of which are arranged adjacent to each other, 105 a knife blade supporting table arranged in operative relation to the grinding faces of said wheels, means for providing a universal horizontal movement of the table to permit the blade when supported thereon to be 110 moved into engagement with the operative faces of each of the several grinding wheels in a manner to square the edges of the tang.

4. A machine for squaring the tangs of 115 knife blades, comprising a series of grinding wheels, the operating faces of two of which are arranged in opposite relation to each other, the operating face of a third wheel being arranged intermediate of and at a right angle to that of the first mentioned wheels, a movable knife blade supporting table adapted to be moved as against the grinding face of one of the wheels for grinding one edge of the tang and then 120 moved against the second wheel for grinding another edge of the tang by a continuous horizontal movement of the work table and with one setting of the blade thereon, 125 said table adapted to be moved away from 130

- said second wheel angularly to said movement between the wheels.
5. A machine for squaring the tangs of knife blades, comprising a bed, a series of 5 grinding wheels mounted upon the bed, a movable table adapted to support and guide a knife blade into engagement with the operative faces of the grinding wheels, a pedestal upon which the table is mounted, 10 and guiding means carried by the table for engagement of the table carrying pedestal whereby the edges of the blade to be ground are properly fed to the grinding wheels.
6. A machine for squaring the tangs of 15 knife blades, comprising a bed having an opening therein, a series of wheels mounted upon the bed, a pedestal hingedly supported on the bed and disposed through said opening, means for guiding the engagement of 20 the pedestal with the edges of the opening, a knife blade supporting table carried upon the pedestal for carrying the knife blade to the respective grinding wheels to be operated upon.
- 25 7. A machine for squaring the tangs of knife blades, comprising a bed having an opening therethrough, a series of grinding wheels mounted upon the bed and having their grinding edges positioned adjacent to 30 each other, and above the opening in the bed, a hanger secured to the underside of the bed, a pedestal pivotally mounted in the hanger, guiding means upon the bed to be engaged by and to guide the pedestal with 35 relation to the operating faces of the wheels, a knife blade supporting table mounted upon the pedestal and adapted to support and carry a knife blade against the several edges of the grinding wheels.
- 40 8. In a machine for grinding the tangs of knife blades, the combination with a bed having an opening therein, a series of grinding wheels mounted upon the bed and positioned with relation to the opening, a 45 hanger secured to the under side of the bed, a cradle swivelly supported in the hanger, a pedestal carried by the cradle adapted to engage and be guided by the edges of the opening in the bed, and a knife 50 blade supporting table mounted upon the pedestal and adapted to carry the blades to the several grinding wheels.
- 55 9. In a machine for grinding the tangs of knife blades, the combination with a bed, of a series of grinding wheels mounted thereon, a knife blade supporting table, a swiveled pedestal upon which the table is mounted, a swinging cradle in which the pedestal is swiveled, means for adjusting 60 the movement of the pedestal relative to the cradle, and means for limiting the guided movements of the pedestal and its table with relation to grinding edges of the wheels.
10. In a machine for squaring the tangs 65 of knife blades, the combination with a grinding wheel having a beveled periphery, of a hinged cradle, knife blade supporting means carried by the cradle and adapted to be moved toward and from the operative periphery of said wheel to grind the edge 70 of the tang of a blade positioned upon the supporting means.
11. In a machine for squaring the tangs 75 of knife blades, the combination with a grinding wheel having a beveled periphery, of a swinging pedestal, a knife blade supporting table carried by the pedestal and adapted to be moved toward and from the operative periphery of said wheel to grind 80 the edge of the tang of a blade positioned upon the table, means for adjusting the pedestal and its table to vary the angle of the cut upon the tang.
12. In a machine for squaring the tangs 85 of knife blades, the combination of a series of grinding wheels having beveled peripheries, a swinging pedestal, a knife blade supporting table carried by the pedestal and adapted to be moved toward and from each 90 of the grinding wheels, means for limiting the feeding movement of the pedestal and its table to insure uniform cutting operations on the tang, and means for holding a knife blade upon the table with its tang 95 free to be operated upon.
13. In a machine for grinding the tangs 100 of knife blades, the combination with a series of grinding wheels, of a pedestal thereon having universal swinging movement, a table mounted thereon and arranged adjacent to said wheels, means for positioning a knife blade upon the table, and devices to guide the travel of the pedestal in a way to successively feed the tang of the 105 knife blade against each of the said wheels for grinding the several edges of the tang.
14. In a machine for squaring the tangs 110 of knife blades, the combination of a series of grinding wheels, of a knife blade supporting table for holding a knife blade in a manner to permit operations upon its tang, means for affording said table universal horizontal movement to bring the several edges 115 of the tang into engagement with the operative faces of the respective grinding wheels.
15. In a machine for squaring the tangs 120 of knife blades, the combination with a bed, of a series of three grinding wheels, a means for adjusting the position of each of the wheels with relation to the other two wheels so as to position their cutting edges close to or far from each other, a movable knife blade supporting table mounted to be moved so that the blade carried thereby will be engaged by each of the three grinding wheels, 125 a swinging cradle member supported beneath the table, a pedestal carried by the

cradle and upon which the table is supported, a handle for directing the movement of the pedestal and table, and means for operating the pedestal and table separately or 5 together or independent of each other.

16. In a grinding machine of the class described, the combination with a series of three grinding wheels, positioned adjacent to each other, a universally movable blade 10 carrying-table adapted to be moved forward by a continuous movement of the table to the operating faces of said wheels, to insure the grinding of the three edges of the tang by said continued movement of the table.

15 17. In a grinding machine for squaring tangs of knife blades, the combination of a bed, three grinding wheels mounted thereon, a knife blade supporting table being supported upon the pedestal, means for guiding 20 the feeding movement of the pedestal in relation to the cutting edges of the grinding wheels, and means for limiting the out-

ward movement or rested position of the pedestal and table when not in use.

18. In a knife blade grinding machine, the 25 combination of a bed, a series of three grinding wheels, a handle secured to the bed, a hanger secured to said bed, a yoke pivotally supported in the hanger, a cradle pivotally supported in the yoke, a pedestal mounted 30 for rotary movement in the cradle, means for limiting the amount of said movement, a knife blade table mounted upon the pedestal and adapted to move therewith in operative relation to the grinding wheels to insure a 35 grinding operation upon each of the three edges of the knife blade tang.

Signed at Bridgeport, in the county of Fairfield and State of Connecticut, this 18th day of January, A. D. 1923.

EDWARD J. CONKLIN.
